Des. 240,827

Patented Aug. 3, 1976

240,827

COOLING UNIT FOR ELECTRONIC ENCLOSURES

Francis U. Hill, 1801 Lyndon Road, San Diego, Calif. 92013, and Albert James Carpenter, 3185 Blenkarne Drive, Carlsbad, Calif. 92008

Filed Sept. 13, 1974, Ser. No. 505,722

Term of patent 14 years

Int. Cl. D23—04

U.S. Cl. D23—141

FIG. 1 is a perspective view of a cooling unit for electronic enclosures, showing our new design.

FIG. 2 is a side elevational view as taken from the left rear of FIG. 1.

FIG. 3 is a side elevational view as taken from the right rear of FIG. 1.

FIG. 4 is a bottom plan view thereof.

We claim:

The ornamental design for a cooling unit for electronic enclosures, substantially as shown.
